UNITED STATES PATENT OFFICE.

BENJAMIN HIRSCHHORN AND LOUIS HIRSCHHORN, OF NEW YORK, N. Y., ASSIGNEES,
BY MESNE ASSIGNMENTS, TO MILLIE PATENT HOLDING CO. INC., OF NEW YORK,
N. Y., A CORPORATION OF NEW YORK.

TEA CARTRIDGE.

Application filed August 5, 1920, Serial No. 401,292. Renewed April 3, 1923.

To all whom it may concern:

Be it known that we, BENJAMIN HIRSCHHORN and LOUIS HIRSCHHORN, citizens of the United States and Austria, respectively, and residents of the city of New York, county of Bronx, and State of New York, have invented certain new and useful Improvements in Tea Cartridges, of which the following is a specification.

10 The present invention relates to a cartridge or ball for percolating or extracting the flavor from tea-leaves or coffee.

15 The main object of the invention is to so construct the cartridge, that, in assembling the same, a preferably flexible suspending means is secured thereto without the aid of special fastening means.

20 Another object of the invention is to provide a wrapper for the cartridge, which is held in position thereon by certain elements of the cartridge proper.

25 A further object of the invention is to provide a cartridge of the character described which is simple in construction, efficient in operation, and which is capable of manufacture on a commercial scale, or in other words one which is not so difficult to produce as to be beyond the reasonable cost of such an article.

30 With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

45 Two of the many possible embodiments of the invention are illustrated in the accompanying drawings, in which:—

50 Figure 1 is a top elevation, partly in section, of a cartridge constructed in accordance with the present invention; Fig. 2 is a section taken on line 2—2 of Fig. 1; Fig. 3 is an enlarged section taken through the joint between the elements of the cartridge; Fig. 4 is a front elevation, partly in section, of a modified cartridge; and Fig. 5 is a

side elevation, partly in section, of the device shown in Fig. 4.

Referring now first to Figs. 1 to 3, inclusive, of the drawings, the numeral 10 indicates a cartridge in the form of a spherical shell, consisting of two semi-spherical members 11 and 12, one or both of which may be perforated. These members may be made of any suitable sheet material, for instance metal, such as block tin. The member 12 is provided with an outwardly projecting annular flange 13, onto which is beaded a similar flange 14 upon the member 11. In this manner a ball is formed, into which has been previously placed a definite quantity of tea-leaves or ground coffee, as the case may be.

For the purpose of facilitating the handling of the cartridge, there is secured thereto a flexible means, such as a string 15, to which is attached at its free end a handle 16, made for instance of cardboard. This string serves also as the means for suspending the cartridge from the receptacle, such as a coffee pot or tea pot, in which the percolation or extraction is to take place. The cord 15 is secured to the cartridge by tying its inner end into a knot 17, and drawing the same through a notch 18 in the flange 14, the notched portion of the flange being then beaded over the flange 13, thereby holding the inner end of the cord in fixed position upon the cartridge. The sheet material, of which the cartridge is formed, is sufficiently thin to permit of the operation described.

In order to obtain a sanitary cartridge, the latter is placed into a wrapper of paper or similar material. This wrapper may be made of two sections, both semi-spherical, denoted in the drawings by the numerals 19 and 20. The section 19 is held upon the shell member 11 by forming in the latter, adjacent the flange 14, an annular groove 21, into which the rim of the wrapper section 19 is placed, it being held therein by friction. The wrapper section 20 is kept upon the shell member 12 by the flange 14, when the latter is beaded over the rim of the said wrapper against the flange 13 of the shell section 12. Adjacent the flanges 14 and 13, the wrapper sections 19 and 20 are provided with scored lines 22 and 23, respectively, running in parallel relation with the said flanges all around the said wrapper

sections. Tongues 24 and 25 are cut into the shell sections 19 and 20, respectively, adjacent the scored lines therein.

When it is intended to brew coffee or tea with the improved device, first the wrapper sections are removed from the cartridge by taking hold of the tongues 24 and 25 and tearing the said sections around the scored lines 22 and 23. The cartridge 5 is then taken hold of by its handle 16 and lowered into the brewing receptacle, the free end of the string and handle being permitted to hang over the mouth of the receptacle, after which the cover of the receptacle is put in place. The cover thus 10 holds the outer end of the cord and handle ready for further operation. Into the receptacle a suitable quantity of boiling water is poured, either before or after the insertion 15 of the cartridge. When sufficient essence is extracted from the grounds or tea-leaves within the perforated ball, the cover is removed from the brewing receptacle and the cartridge withdrawn by grasping the handle 16.

A modification of the invention is shown 20 in Figs. 4 and 5 of the drawings, differing from the one above described in that a bag-like wrapper 26 is used, into which the cartridge is placed. After the cartridge has 25 been inserted, the mouth of the wrapper is puckered and the string 15, which extends through the mouth, wound around the wrapper below its mouth, thereby holding the wrapper in position upon the cartridge.

Otherwise the construction and operation of the device are similar to those of the cartridge shown in Figs. 1 to 3, inclusive, of the drawings.

The percolator cartridges made in accordance with this invention form convenient packages for the transportation and use of the substances contained therein, and, as such, may be articles of merchandise.

What we claim is:—

1. A cartridge for extracting essence from coffee or tea, comprising a perforated container made of two sections united by means made integral therewith; a string attached to said container, and a wrapper enclosing said container held thereon by certain elements constituting the cartridge.

2. A cartridge for extracting essence from coffee or tea, comprising a perforated container, a string attached thereto, and a wrapper enclosing said container held thereon by certain elements constituting the cartridge.

3. A cartridge for extracting essence from coffee or tea, comprising a perforated container, a string attached thereto, and a bag-like wrapper enclosing said container, the mouth of said bag being puckered and said string being wound around the same below its mouth.

Signed at New York, in the county of New York and State of New York, this 25th day of June, A. D. 1920.

BENJAMIN HIRSCHHORN.
LOUIS HIRSCHHORN.
